UNITED STATES PATENT OFFICE.

ERNEST C. PRESCOTT, OF HAVERHILL, MASSACHUSETTS.

COMBINED KITCHEN AND IRONING TABLE.

1,069,978.

Specification of Letters Patent.

Patented Aug. 12, 1913.

Application filed January 14, 1913. Serial No. 741,910.

To all whom it may concern:

Be it known that I, ERNEST C. PRESCOTT, a citizen of the United States, residing at Haverhill, in the county of Essex and State 5 of Massachusetts, have invented an Improvement in Combined Kitchen and Ironing Tables, of which the following is a specification.

This invention relates to certain improvements in kitchen or laundry tables, and more particularly to certain improvements in a table of this character which is adapted both for use as an ironing table and for a kitchen or dining table.

15 The object of my invention is to provide a table of the above described character with an improved and simplified construction, whereby it may be readily converted into an ironing table.

20 I accomplish this object by the means shown in the accompanying drawing, in which,

Figure 1 is an end elevation of a table provided with my invention and arranged 25 in position for use as a kitchen or dining table. Fig. 2 is a plan view of the table showing the parts in position for use as an ironing table. Fig. 3 is a side elevation with the parts in the position of Fig. 30 2. Figs. 4 and 5 are detail views of a form of hinge and hinge connection which I preferably employ.

As shown in the drawing the top of the 35 table comprises a main section *a*, mounted upon a standard *b*, and a leaf section *c*, which is connected by hinges to one edge portion of the section *a* in the usual manner. A pair of brackets *d* are connected to the main part of the table and are adapted 40 to be swung outwardly to support the section *c*, as shown in Fig. 1, or to be folded beneath the section *a*, as shown in Figs. 2 and 3, when it is desired to lower the leaf section *c*, or to fold it over the section *a*, 45 as hereafter described.

According to my invention I secure an ironing-board middle section *e* to the under side of the leaf section *c*, by any suitable means, as screws, said section terminating 50 short of the ends of the leaf section *c*, as shown in Fig. 3, providing supporting end portions, as hereinafter described. End sections *f* and *g* are connected by double jointed hinges *h* to the ends of the middle 55 section *e* and are adapted to form with the section *e* a complete ironing-board of the

usual form, and to be folded onto the outer side of the middle section *e*, as shown in the dotted position of Figs. 2 and 3, the ends of said sections moving into close 60 proximity when held in this position, so that they may be conveniently connected together by any suitable means as the hook *i*. The abutting edges of the sections *f* and *g* with the middle section *e* are preferably 65 faced with angle-irons *j*, shown in detail in Fig. 5, which act to form a rigid connection therebetween.

With the above described device, when the table is to be used for its ordinary purposes, as a kitchen or dining table, the leaf section *c* will be raised and the brackets *d* will be swung out to the position of Fig. 1, so that said end-portions of said section *c* will rest on said brackets to support the 70 same, in which position the ironing-board *e*, *f*, *g* will be supported on the under side of said section *c*, so that it will in no way interfere with the use of the table for this purpose. When it is desired to use the device for an ironing table, the leaf section *c* will be folded over onto the main section *a*, so that it will rest thereon, as indicated in the dotted position of Fig. 1, and then the 75 end sections *f* and *g* will be disconnected 80 and swung outwardly to the full line position of Figs. 2 and 3, in which position they will be supported by said end portions of said section *c*, so that no supporting bracket 85 therefor will be necessary. In this position 90 the sections *e*, *f* and *g* will provide an unbroken, or practically continuous level surface of the desired shape and size for an ironing-table, and which is readily convertible into an ordinary table, in a manner 95 which will be obvious.

I claim:

1. A table comprising a top section arranged to be supported with either side uppermost, an ironing-board middle section secured to one side of said top section, and terminating short of each end thereof, so that said top section has relatively projecting end portions, end sections pivotally connected respectively to the ends of said 100 middle section, and arranged to be supported on the projecting end-portions of said top section when said ironing-board sections are held uppermost, to provide ironing surfaces continuous with the surface of 105 said middle section, and to be folded onto said middle section, so that said top section 110

may be supported by its end-portions when in its opposite position, substantially as described.

2. In combination with a table having 5 main top section a leaf section hinged to one edge of said main section and arranged to be folded thereof, an ironing-board middle section secured to the under side of said leaf section and terminating short of 10 each end thereof to provide supporting end portions and end sections pivotally connected to the ends of said middle section and arranged to be supported on said end portions when the leaf section is supported on

the top section, and to provide ironing surfaces continuous with the surface of said middle section, said end sections being adapted to be folded onto said middle section and having means to secure them in folded position, substantially as described. 15 20

In testimony whereof, I have signed my name to this specification, in the presence of two subscribing witnesses.

ERNEST C. PRESCOTT.
